ATTORNEY

UNITED STATES PATENT OFFICE

HEINRICH OELERICH, OF LEIPZIG, GERMANY, ASSIGNOR TO HEINRICH HOFMANN, OF LEIPZIG, GERMANY

CARBURETOR

Application filed June 1, 1929, Serial No. 367,731, and in Germany March 2, 1929.

The present invention relates to floatless carburetors for internal combustion engines and more particularly to a device for regulating the supply of fuel in such carburetors.

The invention consists in a device of the aforesaid kind, characterized in that a movable regulating member provided with a hollow or chamber is arranged in the carburetor body and that the said regulating member is provided with any desired number of outlet ports of any desired size and shape through which the fuel supplied passes onward into the channels leading to the suction pipe. When the said regulating member is operated the outlet ports provided in it are opened or closed successively during its movement for the purpose of supplying to the internal combustion engine a quantity of fuel corresponding to its consumption. In this manner it is rendered possible to regulate the fuel supply to the greatest possible extent, and always to supply to the engine the particular quantities of fuel which it requires for yielding the particular outputs required from time to time. The aforesaid regulating member may be constructed in the form of a rotary valve, slide valve, piston valve, cock, or the like and may likewise be employed for shutting off the fuel supply completely. The outlet ports provided on the said regulating member preferably lead into a recess provided in the carburetor casing from which recess the conduits leading to the suction pipe are branched off.

The regulating member may also be positively connected with the member for regulating the air supply, such as a throttle valve, rotary valve or the like in order to be able always to supply to the engine an exactly regulated fuel mixture. The device according to the invention is applicable to carburetors of any kind for example, it may be employed for float and jet carburetors, or the like.

A preferred constructional form according to the invention is diagrammatically illustrated by way of example on the accompanying drawings, in which:

Fig. 1 shows the regulating member in longitudinal section,

Fig. 2 shows the regulating member in cross section taken on line A—B of Fig. 1,

Fig. 3 shows the regulating member in elevation, and

Fig. 4 shows, by way of example, a particular constructional form of a floatless carburetor in which a regulating member according to the invention is positively connected with a throttle valve so that the said regulating member is positively moved when the throttle valve is adjusted.

Referring to the drawings, the reference letter *a* denotes a carburetor casing in which a regulating member *b* shown as a rotary valve is arranged, which regulating member is provided with a hollow or chamber *c* and with a number of outlet ports *d* of any desired size and shape, through which latter the fuel (which may, for example, be admitted through the passage *e*) passes onward to the suction pipe *f* of the carburetor or the engine. The outlet ports *d* preferably open into a recess *g* provided in the carburetor casing, from which recess the conduits *h* leading to the suction pipe *f* branch off. When the regulating member *b* is operated, the outlet ports *d* are during the movement of the said regulating member, successively opened or closed in such manner that at any given time only just sufficient fuel is supplied to the induction pipe *f* as is required by the engine in accordance with its output. The supply of fuel to the interior of the regulating member *b* may be effected for example by means of conduits *i* and *e*.

The regulating member *b* may advantageously be positively connected with the member for regulating the supply of air, for instance, throttle valve, rotary valve or the like, as indicated at *k* in order to render it possible always to supply to the engine an exactly proportioned uniform fuel mixture.

A particular constructional form of this kind is shown diagrammatically in Fig. 4.

By means of the regulating device above described and illustrated in the accompanying drawings, it is rendered possible to regulate exactly the quantities of combustible mixture supplied to the engine so that at any given time only so much combustible mixture is formed as is necessary for attaining the desired output. It is to be un-

derstood that the device according to my invention is intended to be applied only to floatless carburetors.

I claim:

- 5 1. In a floatless carburetor for internal combustion engines, the combination of: a carburetor body, a throttle valve in said carburetor body, a shaft upon which said throttle valve is mounted, an air admission inlet admitting air to said throttle valve, a fuel nozzle discharging in said carburetor body anterior to the throttle, a fuel regulating member arranged in said carburetor body on said shaft, a chamber in the interior of said regulating member, means for supplying fuel to said chamber, a plurality of outlet ports in said regulating member, and channels in the carburetor body connecting said outlet ports with said fuel nozzle whereby fuel is supplied in predetermined quantity anterior to the throttle valve.
- 10 2. In a floatless carburetor for internal combustion engines, the combination of: a carburetor body, a throttle valve in said carburetor body, a shaft upon which said throttle valve is mounted, an air admission inlet admitting air to said throttle valve, a fuel nozzle discharging in the said carburetor body anterior to the throttle, a fuel regulating member arranged in said carburetor body on said shaft, a chamber in the interior of said regulating member, means for supplying fuel to said chamber, a plurality of outlet ports in said regulating member, a sec-
- 15 ond chamber in the carburetor body located immediately anterior to the said outlet ports, and channels in the carburetor body connecting said outlet ports with said fuel nozzle, whereby fuel is supplied in predetermined quantity anterior to the throttle valve.
